UNITED STATES PATENT OFFICE.

FRANK E. EHRHARDT, OF SAN FRANCISCO, CALIFORNIA.

SANITARY-COVER ATTACHMENT FOR CUSPIDORS.

1,404,943.

Specification of Letters Patent. Patented Jan. 31, 1922.

Application filed February 28, 1921. Serial No. 448,494.

To all whom it may concern:

Be it known that I, FRANK E. EHRHARDT, a citizen of the United States, residing in the city and county of San Francisco and

5 State of California, have invented a new and useful Improvement in a Sanitary-Cover Attachment for Cuspidors, of which the following is a specification.

10 My invention relates to improvements in sanitary cover attachments for cuspidors and the like wherein the two halves of a split cover operate in conjunction with levers on either side of a base containing a cuspidor to separate said halves to render said cuspidor accessible when either one of said levers is depressed.

15 The primary object of the present invention is to provide an improved sanitary cover attachment for cuspidors and the like.

20 A further object is to provide an improved device of the character described having improved means for rendering the cuspidor accessible.

25 A still further object is to provide improved means of the character described which shall be adapted for attachment to cuspidors of various sizes and shapes without altering the operating principle of said attachment.

30 It is also an object of the present invention to provide an improved sanitary cover attachment for cuspidors and the like which may be attached to present cuspidors without altering the same in any manner.

35 I accomplish these and other objects by means of the improved device disclosed in the drawings forming a part of the present specification wherein like characters of reference are used to designate similar parts 40 throughout the said specification and drawings, and in which:

Fig. 1 is a broken side elevation of my improved device attached to one form of cuspidor;

45 Fig. 2 is a plan view, partly in section, of Fig. 1;

Fig. 3 is a view disclosing the same device attached to a cuspidor of a larger and different shape.

50 Referring to the drawings the numeral 1 is used to designate a base arranged to receive a cuspidor 2 and having upwardly extending lugs 3 formed on opposite sides of said base 1.

55 A split cover, comprising arcuate halves 4, is pivotally mounted over said cuspidor 2

and arranged to cover the top thereof, by means of downwardly extending legs 6 which are pivotally mounted upon the upper ends of the lugs 3 of the base 1. 60

The legs 6 are provided on opposite sides thereof with apertured lugs or projections 7 which are pivotally connected by means of links 8 to a pair of levers 9 extending in opposite directions and pivotally connected 65 to opposite sides of the base 1 so that the device may be operated from either side.

In operation, when either one of the levers 9 is depressed by the foot of an operator, or otherwise, the links 8 will separate the two 70 halves 4 of the cover to uncover the top of the cuspidor 2 as disclosed in dotted lines in Figs. 1 and 3 of the drawings, against the tension of a suitable spring 12 interposed between the lugs or projections of the legs 75 6 of the cover portions 4.

When the pressure is released from the levers 9 the tension of the spring 12 will return the halves 4 of the cover to normal position to close the top of the cuspidor. 80

To remove the cuspidor 2 from the device for cleansing or other purposes, either lever 9 is depressed to separate the covers 4 when the said cuspidor 2 may be removed from the device, cleansed and returned and the 85 pressure then released from said levers 9 to cover said cuspidor 2.

The heavy dotted outline in Fig. 1 of the drawings is to disclose another form of cuspidor which may be enclosed within the 90 device without altering same.

It is obvious from the foregoing that I have provided a new and improved sanitary cover attachment for cuspidors and the like wherein said cuspidor may be easily and 95 readily rendered accessible and wherein the said cuspidor is normally closed to prevent exposure to view of the contents thereof.

It is also obvious that by providing a cover which must be operated before the 100 cuspidor may be used, I have eliminated the objectionable custom of attempting to expectorate into a cuspidor from a distance where the inaccuracy of markmanship often results in the deposit of sputum on the outer 105 surface of the vessel or on the floor adjacent thereto.

Having thus described my invention, what I claim as new and desire to secure by Letters Patent is:

1. A sanitary cover attachment for cuspidors comprising a base plate having up-

wardly extending lugs formed integral therewith; a split cover pivotally mounted upon the lugs and arranged to normally extend over the top of a cuspidor placed upon the 5 base plate, said cover being arranged to be separated to uncover said cuspidor; a pair of levers pivotally mounted upon diametrically opposed sides of the base and arranged to extend around the opposite side of the cus- 10 pidor; and links pivotally connected to the cover portions and to the levers to separate said cover portions when either of the levers is depressed.

2. A sanitary cover attachment for cus- 15 pidors comprising a base plate having upwardly extending lugs formed integral therewith; a split cover having its portions pivotally mounted upon a common pivot bearing upon said lugs and arranged to normally ex- 20 tend over the top of a cuspidor placed upon the base plate, said portions being arranged to be separated to uncover said cuspidor; a pair of levers pivotally mounted upon dia- 25 metrically opposed sides of the base plate and arranged as loops extending around the sides of the cuspidor, said levers being pivotally and slidably connected; and links pivotally connected to the cover portions and to the levers to separate said portions when 30 either of the levers is depressed.

3. A sanitary cover attachment for cus- 35 pidors comprising a base plate having upwardly extending lugs formed integral therewith; a split cover having its portions pivotally mounted upon a common pivot bearing upon said lugs and arranged to nor-

mally extend over the top of a cuspidor placed upon the base plate, said portions being arranged to be separated to uncover said cuspidor; a pair of levers pivotally mounted upon diametrically opposed sides of the cuspidor, said levers being pivotally and slidably connected; links pivotally connected to the cover portions and to the levers to separate said portions when either of the levers is 45 depressed; and means for normally retaining said cover portions in a closed position.

4. A sanitary cover attachment for cuspidors comprising a base plate having upwardly extending lugs formed integral 50 therewith; a split cover having its portions pivotally mounted upon a common pivot bearing upon said lugs and arranged to normally extend over the top of a cuspidor placed upon the base plate, said portions being arranged to be separated to uncover said cuspidor; a pair of levers pivotally mounted upon diametrically opposed sides of the base plate and arranged as loops extending 55 around the sides of the cuspidor, said levers being pivotally and slidably connected; links pivotally connected to the cover portions and to the levers to separate said portions when either of the levers is depressed; and springs connected between the cover portions to nor- 60 mally hold said portions in a closed position and to return said portions to said closed position after being displaced therefrom by depression of one of the levers.

In witness whereof, I have hereunto set 70 my signature.

FRANK E. EHRHARDT.
